UNITED STATES PATENT OFFICE

108,941

DESIGN FOR A MOVING PICTURE FILM SHIPPING CASE

Jacob M. Goldberg, Denver, Colo.

Application January 29, 1938, Serial No. 74,699

Term of patent 14 years

To all whom it may concern:

Be it known that I, Jacob M. Goldberg, a citizen of the United States, residing at the city and county of Denver and State of Colorado, have invented a new, original, and ornamental Design for Moving Picture Film Shipping Cases, of which the following is a specification, reference being had to the accompanying drawing, forming part thereof.

In the drawing:

Figure 1 is a side elevation of a moving picture film shipping case showing my new design;

Figure 2 is a top plan view thereof;

Figure 3 is an elevation, looking in the direction of arrow 3 in Fig. 1; and

Figure 4 is an elevation, looking in the direction of arrow 4 in Fig. 1.

I claim:

The ornamental design for a moving picture film shipping case, as shown.

JACOB M. GOLDBERG.
